US00D712101S

(12) **United States Design Patent**
Elmer et al.

(10) **Patent No.:** **US D712,101 S**
(45) **Date of Patent:** **** Aug. 26, 2014**

(54) **VACUUM CLEANER**

(71) Applicants: **Thomas Elmer**, Brøndby (DK); **Henrik Mathiassen**, Aargus (DK); **Rasmus Falkenberg**, Aargus (DK); **Adnan Oprasic**, Aargus (DK)

(72) Inventors: **Thomas Elmer**, Brøndby (DK); **Henrik Mathiassen**, Aargus (DK); **Rasmus Falkenberg**, Aargus (DK); **Adnan Oprasic**, Aargus (DK)

(73) Assignee: **Nilfish-Advance A/S** (DK)

(**) Term: **14 Years**

(21) Appl. No.: **29/438,537**

(22) Filed: **Nov. 30, 2012**

(51) LOC (10) Cl. **15-05**

(52) U.S. Cl.

USPC **D32/21**

(57) **CLAIM**

We claim the ornamental design for a vacuum cleaner, as shown and described.

DESCRIPTION

FIG. 1 is a front perspective view of a vacuum cleaner showing our new design;

FIG. 2 is a rear perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.
